INVENTOR.
S. M. WARD.
BY *J. Francis Ley*
ATTORNEY.

UNITED STATES PATENT OFFICE

SENA M. WARD, OF BROOKLYN, NEW YORK

SEPARABLE FASTENER

Application filed May 4, 1932. Serial No. 609,301.

My present invention relates to improvements in separable fasteners.

The principal object of the invention is to provide a separable fastener particularly, though not exclusively, designed and intended for use on and in connection with wearing apparel, whereby the separate parts of the fastener may be attached to separate garments or separate parts of a garment to secure the same together. For instance, girdles and corsets are usually provided with depending garters quite commonly permanently attached to the girdle or corset, so that when the latter are washed it is necessary to also subject the garters to the action of the washing fluid which more or less destroys the elasticity of the garter. In accordance with my invention, I provide a separable fastener, whereby the garter may be detachably secured to the girdle so that when the girdle is washed the garters may be easily detached and later attached. I do not limit the invention to use in this particular combination as the same is susceptible of use in connection with attaching various articles, and other items of wearing apparel.

The objects of the invention include the provision of a fastener which may be made at a minimum of expense; and embodying a construction and arrangement of parts providing a flat or thin fastener so that a noticeable bulge will not be created thereby to detract from the appearance of garments worn thereover.

The foregoing objects are accomplished by the provision of a resilient retaining member and a rigid retained member both embodying a minimum amount of material and capable of being made by a very simple stamping operation.

In the accompanying drawing,

Fig. 1 is a view illustrating fasteners embodying the invention applied to a girdle and garters;

Fig. 2 is a perspective view of the parts detached and in related position for assembly;

Fig. 3 is a front elevation of the parts shown in Fig. 2 assembled;

Fig. 4 is a sectional view on the line 4-4 of Fig. 3; and

Fig. 5 is a view similar to Fig. 3 showing a modification in size and attachment loops.

Referring first to Fig. 2 of the accompanying drawing, "A" designates the retained member of the fastener and comprises a flat and preferably thin rigid sheet formed with an attachment loop 6 at its top, so that, as shown in Fig. 1, the same may be secured to a girdle or other part by looping stitches through the material and around the top of the loop 6 and through the slot 7 formed in the loop. Depending from the attachment loop is a tongue or extension 9 having its lower edge bent outwardly at substantially right angles to the tongue 9 to form a retaining flange 10. "B" designates the retaining member of the fastener which also has an attachment loop 11 with a slot 12, and thereabove a substantially flat U-shaped part formed by bending a strip upon itself, as at 14, to provide one arm or keeper 15, the lower end of which terminates preferably slightly above the top edge of the loop 11 and over the other arm 13 of the U-shaped member. The part "B" is made of resilient metal preferably of a rust proof or stainless character or plated with a rust proof coating. The resilience of the metal and the bend or crease 14 forms a resilient connection between the arms so that if 15 is lifted away from the part 13, it will return to its original position, which is either in contact with the part 13 or in very close proximity thereto, when released. A portion of the crease 14 is cut away as indicated at 16 to provide an opening in the top of the retaining member through which the tongue or extension 9 on the retained part "A" may be inserted. As clearly shown in Figs. 2 and 4, the arms 15 and 13 converge toward the loop 11, that is, they are shown as being spaced apart further at the crease 14 than at the lower end of the flap 15. The spacing at the opening 16 need only be sufficient to enable insertion of the flange 10 which will force the flap 15 away from the wall 13 as it is moved downwardly, and of course as soon as the flange 10 passes the lower end of the

flange 15, the latter will spring back against the face of the tongue 9 above the flange 10, thus preventing separation of the parts A and B unless and until the flap 15 is raised 5 sufficiently to permit the flange 10 to pass between it and the wall 13. This may be quickly and easily accomplished, simply by inserting the fingernail or any thin and sufficiently strong element between the flap 15 10 and the tongue 9 and pushing the flap 15 outwardly.

Preferably, the relative lengths of the tongue 9 and the flap 15 is such that the bottom of the loop 6 will contact the crease 14 after 15 the flange 10 has been engaged by the lower edge of the flap 15 upon insertion of the tongue 9 through the opening 16 and passage of the flange 10 to its lowermost locked position.

(20) In Fig. 5, I have shown a small sized fastener which is identical with the fastener shown in the other figures in that the parts A and B are constructed in the manner specified but the retaining loops 6' and 11' respectively are not as long as those shown in the other figures relative to the width of the other parts of the fastener.

The construction and operation of the fastener should be clearly understood from 30 the foregoing and no reiteration will be given, but I desire to point out that the device can be made of various types of metal and in various sizes and that the relative length and width of the retaining flap 15 and tongue 9

35 and flange 10 may be varied at will, as the fastener is adapted for use with different articles. However, the device is especially useful in connection with ladies' wearing apparel, in that it provides no sharp edges or points to cut or catch on the garments which may come into contact therewith, and it will be understood that in actual use, the edges would not necessarily be as distinct and clearly defined as shown in the drawing for 40 the purposes of illustration, but may be rounded. Furthermore, the extreme thinness of the device and its ease and effectiveness of operation make it particularly suited for 45 feminine wearing apparel.

(50) I claim:—

1. A separable fastener comprising a retaining member of flat resilient metal bent upon itself to provide a relatively flat substantially U-shaped part in cross-section 55 with a portion of its crease cut out to provide an opening therethrough, an end of one of the arms of said member being free and normally urged toward the other arm, and a retained member having a tongue insertible between said arms through said opening, and a projection on the end of said tongue for locking engagement with the free end of said one arm.

60 2. A separable fastener comprising a retaining part having means for attaching it

to a garment or the like, said member having superimposed plates resiliently connected at one end and one of said plates having a free edge at its end opposite said connected end, said free edge being normally urged toward 70 said other plate, a retained member having means for attaching it to a garment or the like and having a substantially rigid extension, said retaining member having an opening at the connected ends of the plates through which said extension may be inserted, and said extension having a keeper at its end for locking engagement with said free end of said one plate when the extension is passed through said opening and between said plates.

3. A separable fastener comprising a retaining member of flat resilient metal having a portion folded upon itself to provide a substantially flat U-shaped part in cross-section, with a narrow elongated opening extending through the crown of the fold, the extremity of the free arm of said member being normally urged toward the face of the other arm, and a retained member of flat metal having an extension slightly narrower than 85 said opening and adapted to be inserted therethrough between the arms of the U-shaped member, the entering end of said extension being flanged at its extremity to provide a lateral shoulder engageable beneath the edge of the free arm when the parts are assembled to detachably connect the two members.

4. A separable fastener comprising a retaining member of flat resilient metal having a portion folded upon itself to provide a substantially flat U-shaped part in cross-section, with a narrow elongated opening extending through the crown of the fold, the extremity of the free arm of said member being normally urged toward the adjacent face of the other arm, and a substantially T-shaped complementary member of flat metal having means at its upper end to attach it to a garment with a portion adapted to be inserted through the said elongated opening and between the arms of the U-shaped member, the extremity of the end of said portion being flanged to provide a lateral shoulder adapted to engage beneath the lower edge of the said free arm when the parts are assembled to provide a detachable connection between the two members.

Signed at New York city in the county of 120 New York and State of New York this 2nd day of May A. D. 1932.
